UNITED STATES PATENT OFFICE.

HAROLD F. SHEPHERD, OF GROVE CITY, PENNSYLVANIA, ASSIGNOR TO BESSEMER GAS ENGINE COMPANY, OF GROVE CITY, PENNSYLVANIA, A CORPORATION OF PENNSYLVANIA.

HOT-PLATE APPARATUS FOR EXPLOSIVE-ENGINES AND THE LIKE.

1,258,156.

Specification of Letters Patent.

Patented Mar. 5, 1918.

Application filed November 25, 1916. Serial No. 133,371.

To all whom it may concern:

Be it known that I, HAROLD F. SHEPHERD, a citizen of the United States, residing at Grove City, in the county of Mercer and 5 State of Pennsylvania, have invented new and useful Improvements in Hot-Plate Apparatus for Explosive-Engines and the like, of which the following is a specification.

This invention relates to hot plate apparatus for explosive engines and the like and consists in certain improvements in the construction thereof as will be hereinafter fully described and pointed out in the claims.

In the so-called hot bulb engine, the plate 15 is maintained at a temperature at which the explosive mixture will ignite. The temperature of the plate is controlled by the heat produced in the hot bulb through the burning of the gases exploded in the running of the engine. This heat varies with 20 the intensity of the explosion and a variation in the amount of gases burned and consequently the temperature of the plate varies. This variation is objectionable. If 25 the temperature is sufficient to give proper ignition at light loads the higher temperature incident to the burning of a greater amount of gases for the heavier loads tends to crack the oil used in the mixture and this 30 produces carbon or an objectionable residue. To obviate this difficulty several plans have been adopted, the usual one being to inject water with the explosive mixture and vary the amount of water introduced sufficiently 35 to control the temperature within working limits. This adds to the working parts of the engine and is not entirely satisfactory in its results.

The present invention is designed to automatically control the temperature of the hot plate of the hot bulb so as to give it a proper ignition temperature and still prevent a very wide variation from this temperature.

The invention is illustrated in the accompanying drawings as follows:—

Figure 1 shows a central vertical section through a gas engine cylinder showing my invention.

Fig. 2 shows a similar view of an alternative construction.

1 marks the cylinder, 2 the piston, 3 the cylinder head, 4 the jacket for the cylinder head, 5 the ignition or combustion chamber

and 6 the injector which may be any of the well-known forms injecting fuel alone or 55 fuel and air depending somewhat on the type of the engine.

The hot plate 7 forms one wall of a receptacle 8. The receptacle 8 is mounted in a water-jacketed housing 9 and an insulating space 10 is provided between the walls of the receptacle 8 and the housing 9. The receptacle has a flange 11 at its upper end which rests on the face of the housing 9. A condensing plate or head 12 is arranged 65 over the receptacle and clamps the flange 11 on the face of the housing 9. The condensing plate has a cavity 13 through which water may be circulated, the pipes 14 being provided for this purpose.

A liquid 16 is provided for the receptacle and has a level, as shown at X, covering the plate 7. This liquid is one that has a vaporizing or boiling point at or above the ignition point of the explosive mixture. I have 75 found sulfur having a vaporizing point of 446° centigrade admirably adapted for the purpose. For some purposes mercury having a boiling point of 360° centigrade may be used.

An auxiliary bulb 17 is provided which may be heated by a torch, or otherwise, for the starting of the engine.

In the operation of the device, the burning gases in the combustion chamber heat 85 the plate 7. This heat is absorbed by the liquid 16. When the liquid reaches the boiling point it vaporizes and the vapor coming in contact with the plate 12 is cooled and condensed and returns to the body of the 90 liquid 16. The rapidity of this vaporization depends upon the heat generated in the combustion chamber and this is dependent upon the amount of oil burned, in other words, the load at which the engine is running. The device, therefore, works automatically. With a greater vaporization there is a greater condensation, with a smaller vaporization a smaller condensation. The space between the liquid 16 and 100 the plate 12 insulates the hot plate from the condenser. The condenser may be placed at some distance from the receptacle 8 but for convenience is placed directly over it, as shown. It should be, however, of sufficient 105 capacity to readily condense all vapor that

may be formed in the operation of the device under the heaviest loads to which the engine is subjected.

It may be desired with variations of mixture to vary the temperature of the plate 5. This may be accomplished by varying the pressure in the receptacle 8. A pipe 15 is provided for this purpose and by putting the receptacle 8 under pressure by introducing air or a neutral gas the liquid in the receptacle may be varied to any pressure desired and its boiling point varied. With this variation in boiling point there is a similar variation in the plate 7. While I have shown and preferred the dissipation of the heat from the liquid 16 by vaporizing this liquid and condensing the vapor, I do not, in the broadest phases of my invention, wish to be limited to such a structure.

In the alternative construction shown in Fig. 2, 1 marks the cylinder and 2 the piston. The head 18 is arranged on the cylinder and this is connected by an insulating neck 19 with the combustion or ignition chamber 20. An injector 21 is provided for introducing fuel or fuel and air as may be desired. A hot plate 22 forms one wall of the combustion chamber. A receptacle 23 surrounds the hot plate and this is closed by a plug 24. A liquid 25, such as sulfur, is placed in the receptacle having preferably a level at Y. In this case the walls of the receptacle are provided with radiating ribs 26 these walls thus forming a condenser for the vapor given off by the liquid 25 when it is heated above the vaporizing point.

An auxiliary hot bulb 27 is provided for starting the engine. The operation is similar to that shown in the structure of Fig. 1 except that the condensation is here accomplished by the air cooled radiating ribs instead of by means of the water circulation as shown in the structure of Fig. 1.

What I claim as new is:—

1. In a hot plate apparatus for explosive engines and the like, the combination of a plate to be heated to ignition temperature; and means for maintaining a liquid in contact with the plate with a vaporizing point at or above ignition temperature.

2. In a hot plate apparatus for explosive engines and the like, the combination of a plate to be heated to ignition temperature; means for maintaining a liquid in contact with the plate with a vaporizing point at or above ignition temperature; and means for dissipating the heat from the liquid.

3. In a hot plate apparatus for explosive engines and the like, the combination of a plate to be heated to ignition temperature; means for maintaining a liquid in contact with the plate with a vaporizing point at or above ignition temperature; means for

dissipating the heat from the liquid through its vapor; and means for condensing the vapor given off by the liquid.

4. In a hot plate apparatus for explosive engines and the like, the combination of a plate to be heated to ignition temperature; means for maintaining a liquid in contact with the plate with a vaporizing point at or above ignition temperature; means for dissipating the heat from the liquid through its vapor; and means for condensing the vapor given off by the liquid and returning the liquid formed by such condensation.

5. In a hot plate apparatus for explosive engines and the like, the combination of a plate to be heated to ignition temperature; and sulfur maintained in contact with the plate for dissipating the heat from the plate.

6. In a hot plate apparatus for explosive engines and the like, the combination of a plate to be heated to ignition temperature; a closed receptacle in which the plate forms a wall adapted to maintain a liquid in contact with the plate; and means for controlling the pressure in the receptacle.

7. In a hot plate apparatus for explosive engines and the like, the combination of a plate to be heated to ignition temperature; a liquid in contact with the plate; and means for dissipating the heat from the liquid, said means varying the amount dissipated automatically as the heat generated by the hot plate varies to maintain the temperature of the plate approximately constant.

8. In a hot plate apparatus for explosive engines and the like, the combination of a plate to be heated to ignition temperature; a closed receptacle in which the plate forms a wall adapted to maintain a liquid in contact with the plate; and condenser apparatus adapted to act upon vapors produced in the receptacle and to return the liquid so condensed.

9. In a hot plate apparatus for explosive engines and the like, the combination of a plate to be heated to ignition temperature; a closed receptacle in which the plate forms a wall adapted to maintain a liquid in contact with the plate, said receptacle having a flanged end; a housing for said receptacle spaced therefrom; a condensing plate forming a cover for the receptacle and adapted to clamp the receptacle on the housing; and means for circulating a liquid through the condensing plate.

10. In a hot plate apparatus for explosive engines and the like, the combination of a plate to be heated, and means for maintaining a liquid in contact with the plate with a vaporizing point at atmospheric pressure at or above ignition temperature.

11. In a hot plate apparatus, the combination of a plate to be heated to ignition temperature the heat to which the plate is

subjected varying with variations in the intensity of explosions of the engine; and means for dissipating the heat of the plate, said means varying the amount dissipated 5 automatically as the heat from the explosions vary to maintain the temperature of the plate approximately constant.

12. In a hot plate apparatus the combination of an explosion chamber; means 10 for introducing fuel to the chamber; a plate

acting on the fuel and subjected to heat varying with the intensity of the explosions; a liquid dissipating the heat from the plate having a vaporizing point at a predetermined desired temperature for the plate; 15 and means for condensing the vapor and returning it to the liquid.

In testimony whereof I have hereunto set my hand.

HAROLD F. SHEPHERD.
